UNITED STATES PATENT OFFICE

129,467

DESIGN FOR A COMBINED RANGE AND KITCHEN HEATER

Elmer D. Pellegrin, Woodstock, Ill., assignor to
Geo. D. Roper Corporation, Rockford, Ill., a
corporation of Illinois

Application March 24, 1941, Serial No. 99,808

Term of patent 7 years

To all whom it may concern:

Be it known that I, Elmer D. Pellegrin, a citizen of the United States, residing at Woodstock, in the county of McHenry and State of Illinois, have invented a new, original, and ornamental Design for a Combined Range and Kitchen Heater, of which the following is a specification, reference being had to the accompanying drawing, forming part thereof.

In the drawing:

The figure is a perspective view of a combined range and kitchen heater showing my new design, the other end of the range which does not show being substantially plain. The small circles appearing on the front panels indicate the

locations for handle attachments and gas cock and oven regulator knobs, which are omitted. The two elongated openings appearing in the upper front panel indicate the locations of drip pan handles, which are also omitted. The dotted lines on the cooking top indicate the position of the lid over the burners.

The dominant features of the design reside in the portions shown in full lines.

I claim:

The ornamental design for a combined range and kitchen heater, substantially as shown and described.

ELMER D. PELLEGRIN.
